UNITED STATES PATENT OFFICE

YVES PAUL GASTON LE PRIEUR AND AUGUSTE LOUIS RICORDEL, OF PARIS, FRANCE,
ASSIGNORS TO "LA PRECISION MODERNE", OF PARIS, FRANCE, A CORPORATION OF
FRANCE

SIGHT FOR ANTI-AIRCRAFT MACHINE GUNS

Application filed October 22, 1930, Serial No. 480,504, and in France March 13, 1930.

We will first recall the principles according to which are made most lines of sight for guns adapted to fire against aerial movable targets.

- 5 These lines of sight must be such that, when the sight glass or similar instrument is directed towards the target, the gun barrel comes automatically into the position required for firing correctly against this target.
- 10 To this end the sight glass is set with reference to the gun, after the two following corrections have been taken into account:

- (a) The correction due to the variable deformation of the trajectory with the varying 15 angles of sight of the target (sight correction);
- (b) The correction required by the displacement of the target during the time of flight of the projectile (displacement correction).

The sight-correction (Figure 1) is based on the well-known principle of the vertical sight. Supposing ab is a gun barrel directed for firing on a target disposed in its horizontal plane (angle of sight zero), the line of sight passes through a foresight b at the end of the gun and through a point c at the end of the vertical back-sight ac . If it is desired to fire on a target at the same distance as the first one but the angle of sight of which is s , an easy calculation based on experience shows it is sufficient to make the gun rotate round a until its end a is brought to b' , the back-sight ac remaining unaltered provided it continues 35 being vertical.

As concerns the corrections of displacement, supposing E (Figure 2) is the actual position of the aircraft, O the end of the gun which is to fire against it, F the future position of the aircraft after a time T equal to the time of flight of the projectile corresponding to a range D equal to OE . If we draw a small triangle oef corresponding to OEF at a reduced scale, the following formula may be used

$$\frac{EF}{OE} = \frac{ef}{oe}$$

50 which means that, if V is the real speed of

the aircraft (including consequently the wind correction) and oe is given a constant value, say 1, the following formula is true:

$$ef = \frac{EF}{OE} = \frac{VT}{D} \quad 55$$

A corrector making use of this formula will comprise a vertical back sight he and an arm ef , the arm fo carrying the sight-glass 60 being connected with a stationary point of the gun O such that $Oe=1$.

Such a corrector has been described, in the prior patent to Yves Le Prieur, No. 1,651,093, of November 29, 1927. 65

In this corrector, the arm parallel to the sight glass is articulated on the one hand at a point of the fire-arm and on the other hand to the end of a vertical rod which is displaced in height so as to materialize the vector ef and which is displaced laterally to the movable target for a length equal to 70

$$\frac{VT}{D} \quad 75$$

For this purpose, the vertical rod is mounted in a carriage sliding horizontally in a cylindrical box with vertical shaft, this box which is adapted to be raised or lowered in a cylindrical casing with vertical shaft is articulated to the fire-arm and adapted to rotate in the said casing. The elevation is given by a vertical displacement of the box in the casing. The plane passing through the axis of the box is directed and also the vertical rod parallel to the speed of the aircraft by a suitable rotation of the box in the casing, the said rotation being controlled by means of an arrow which is directed parallel to the aircraft. An auxiliary device outside the cylindrical casing allows of the product 80 85

$$\frac{VT}{D} \quad 95$$

being formed. The said device has for its object to displace a suitable rack for the length corresponding to the said product and the said rack laterally displaces the carriage 100

bearing the vertical rod for a length equal to

$$\frac{VT}{D}$$

5 through the medium of two screw sleeves and a toothed pinion and a rack.

This device has several drawbacks including the necessity for an auxiliary device for 10 effecting the product

$$\frac{VT}{D}$$

15 Moreover, the sight D must be provided twice, once for producing the elevation for the first drum and once for forming the product

$$\frac{VT}{D}$$

20 The apparatus, which constitutes the subject matter of the present invention has for its object to dispense with the auxiliary device and to necessitate only one operation 25 for introducing the value D in the apparatus. It comprises chiefly an internally and externally threaded ring which supports the cylindrical box and is adapted to be raised and lowered in the casing without being able 30 to rotate; a cylindrical rack engages externally with the threaded ring and internally with the pinion which controls the radial displacement of the carriage. The said rack 35 rotates integrally with a speed abacus but is not able to effect vertical displacements relatively to the said sleeve. The speed abacus is controlled by any suitable means such as endless screw and helicoidal teeth. An 40 internally threaded crown meshing with the threaded ring which supports the cylindrical box allows of giving the elevation. It controls at the same time the vertical displacement in cooperation with the rear sight of 45 a front index which displaces the speed curves. When the rear sight is set, the speed curves adapted to give the vertical rod an eccentricity equal to

$$\frac{VT}{D}$$

50 need only be brought in front of the said index by a rotation of the speed abacus.

Two constructional forms of apparatus in 55 accordance with the invention are shown by way of example in Figures 3 to 10.

Figures 3 to 6 relate to a first form of execution.

Figure 3 is a cross-sectional vertical view 60 through the axis of the cylindrical box and through the axis of the sight-control shaft about on the line 3—3 of Fig. 5.

Fig. 4 is a cross-sectional vertical view 65 through the axis of the speed-control shaft, about on the line 4—4 of Fig. 5.

Figure 5 is a transverse cross-section of the apparatus about on line 5—5 of Fig. 3.

Figure 6 is a perspective view thereof.

Figures 7 to 9 show the simplified form of execution for firing on short and on long 70 ranges.

Figure 7 is a cross-sectional vertical view passing through the axis of the cylindrical box.

Figure 8 is a simplified transversal cross-section showing the control of the carriage.

Figure 9 is a view from above.

Figure 10 shows a form of speed abacus developed in a horizontal plane.

Referring first to Figures 3 to 6, we have shown merely the part of the corrector which serves to set in place the universal joint connected with the arm f o carrying the sight device of the corrector and corresponding to the point f of Figure 2.

This part of the corrector comprises a casing 1 inside which may rise, fall and rotate the cylindrical box 2. In this cylindrical box, the carriage 3 may move radially; this carriage shows a toothwork meshing with the pinion 4 (Figure 3). Another carriage 5, sliding with reference to the carriage 3, is provided with a vertical sleeve 6 containing the rod 7 carrying the universal joint corresponding to point f. The direction arrow is shown at 10. The rotary motion of the cylindrical box in its casing is obtained by acting on this arrow 10; when the tip of the arrow is raised or lowered according to the raising or falling motion of the aircraft, it causes the carriages to move one with reference to the other through the agency of a mechanism which is disclosed in Patent 1,651,093 before mentioned.

The pinion 4 meshes with a circular rack 8 whereby only the vertical movements of the rack produce a rotation of the pinion 4, the rotary movements having no action. Outwardly the circular rack is provided with a thread meshing with the inner thread of a ring 9 provided with an inner and an outer thread.

This ring, which forms the chief part of the present arrangement, carries the cylindrical box 2 in a manner such as will allow its rotation. But the ring itself is only adapted to rise and fall in the casing, without rotating with reference to this casing. The outer thread of the ring 9 meshes with the inner thread of a sun-wheel 11 mounted in a manner such as to be adapted to rotate in the casing 1 but without rising or falling.

The rotation of the sun-wheel 11 is controlled by the pinion 12 (Figure 4) keyed to the stub-shaft 13 the rotation of which is obtained through the range knob 14 (Figures 5 and 6). The vertical displacements of the ring are given out outwardly by the pointer 16 (Figure 6).

The circular rack 8 is connected in rotation with the abacus-cylinder 15 by means of

a finger 8' sliding in a vertical slot 15' provided in the inner wall of the cylinder 15, on the outside of which are drawn the speed abacuses 17 (Figure 6) which are outwardly 5 visible through the apertures 18 provided in the casing. To this end (Figure 3) it meshes with a pinion 19 keyed to the stub shaft 21 which is caused to rotate through suitable intermediary gear wheels by the speed-control 10 knob 22 (Figures 5 and 6).

With regard to the speed abacus, the speed 15 has been indicated in kilometers on each curve to which speed this curve corresponds. Each of these curves is traced through a point. Lengths proportional to the values of 20 sights corresponding to different ranges D are provided as ordinates, a range-graduation being provided at the ordinate axis.

Lengths proportional to $\frac{(t+e)V}{D}$ are provided as abscissæ (e being a supplementary correction for taking into consideration the lost time in manoeuvering). In order to fix 25 the ideas, let us suppose that $D=2400$ meters and $V=30$ kilometers per hour, the operation providing the sight will bring the index 16 in coincidence with the line 2400. The rotation of the abacus will bring the point M in M_1 to the end of the index 16. The angle of 30 rotation will be proportional to MM_1 , hence the value of $\frac{V(t+e)}{D}$ for $D=2400$ and $V=30$ kilometers.

The working of the apparatus is as follows: 35 We begin by setting down the range through rotation of the sight knob 14. The shaft 13 (Figure 4) and the sun-wheel 11 are thus rotated. The rotation of this sunwheel has 40 for its object, as the ring 9 cannot rotate in the casing, to make this ring rise or fall. It raises or lowers the whole of the box 2 with all its contents and in particular the rack 8 the vertical displacement of which is possible 45 with reference to the abacus cylinder 15. As the pinion 4 and the rack 8 are raised simultaneously, there is no relative movement of these two parts one with reference to the other and the action on the sight knob 14 has only 50 as a result the raising or lowering of the box 2 and consequently of the rod 7 and the universal joint representing the point f. The pointer 16 moves at the same time along a scale provided on the edge of the aperture 18 and this displacement is stopped when the desired range is reached on the scale.

We act then on the speed knob 22. The rotation of this knob causes the rotation of the shaft 21 (Figure 3) and through the agency 55 of the pinion 19 the rotation of the abacus cylinder 15. But this rotation of the abacus cylinder 15 causes the rack 8 to rotate. The latter, as the ring 9 cannot rotate, rises or falls as it rotates with reference to this ring. This 60 rise and fall causes a rotation of the pinion

4 and a radial displacement of the carriage 3 and of the rod 7. The action on the knob 22 is continued until the desired speed abacus 17 comes into coincidence with the pointer 16. Obviously the rotation required for this coincidence depends on the position of the index 70 16 with reference to its scale and consequently on the range.

It is thus apparent that the range has an action on the radial displacement of the carriage. 75

The simplified form of execution of Figures 7 to 9 is intended for firing with a certain number of typical speeds and over two kinds of ranges only, short ranges and long ranges. 80

In this apparatus, a casing 31 is also provided wherein may move vertically the cylindrical box 32 inside which moves radially the carriage 33 provided with a toothwork meshing with the pinion 34. Another carriage 35 slides with reference to the carriage 33; it is provided with a vertical sleeve 36 containing the rod 37. The directing arrow is shown at 40. The relative movement of the two carriages is provided as explained 85 hereinabove.

The cylindrical box 32 is carried by an outwardly threaded ring 38, said thread meshing with the inner thread of a sun-wheel 41 adapted to rotate without moving vertically inside the casing 31; this sun-wheel is outwardly provided with notches 42 adapted to be engaged by a tooth 43 (Figures 7 and 9) forming part of a handle 44 urged forward by a spring 45 so as to make the tooth 43 engage a notch 42. But this engagement can be provided only if the tooth 43 is in front of one of the notches 42 corresponding to a given speed; except in such cases, the tooth 43 moves round the sun-wheel 41. The spring-100 urged handle 44 is mounted on an axis 46 integral with an inwardly threaded sun-wheel 47, the thread of which meshes with the outer thread 48 of the circular rack, the part forming the rack being to the inside and meshing with the pinion 34 for displacing the carriage. The rack 48 is adapted to move only vertically. 105

The apparatus is made use of in the following manner: supposing the handle 44 is 110 in the notch 42 to the extreme right, it is pulled so as to disengage the tooth 43. The handle is then turned towards the left so as to bring it in front of the notch 42 corresponding to the speed of the target (proper or effective speed according to the firing method used). By acting thus, the sun-wheel 47 is caused to rotate which in its turn makes the rack 48 rise, so as to rotate the pinion 34 which causes the displacement of the carriage 33. The handle 44 is then allowed to return and the tooth 43 engages the desired notch 42. The handle is now rotated to the end of its path towards the right or the left according as to whether it is desired to fire over short 120 125 130

or long ranges. Under these circumstances, the handle 44 drives simultaneously the sun-wheel 47 and the sun-wheel 41. We provide thus, through the sun-wheel 47, a complementary rise or lowering of the rack 48 which introduces the distance in the eccentricity, and through the sun-wheel 41 a rise or lowering of the ring 38 and consequently of the cylindrical box 32, which provides the sight.

10. What we claim is:—

1. A corrector for the firing of anti-aircraft guns comprising a constantly vertical casing secured to the gun, an inwardly and outwardly threaded ring adapted to rise and fall without rotating inside the casing, a cylindrical box carried by the ring inside said casing, means for displacing said box vertically in the casing in accordance with the range of the target, a carriage carried by the box adapted to be displaced therein according to the speed and range of the target along a radius of the box parallel to the projection of the path of the aircraft, a rod carried by the carriage and pivotally connected with a stationary point of the gun, sighting means carried by said rod, a pinion controlling the radial displacement of the carriage, a rack meshing with the pinion and provided with an outer thread engaging the inner thread of the ring, a cylinder provided with speed curves adapted to rotate with the rack without moving vertically with it, a speed control knob controlling the rotation of the cylinder, an inwardly threaded sun-wheel mounted inside the casing and meshing with the outer thread of the ring and a sight control knob controlling the sun-wheel.

2. A corrector for the firing of anti-aircraft guns comprising a constantly vertical casing secured to the gun, an inwardly and outwardly threaded ring adapted to rise and fall without rotating inside the casing, a cylindrical box carried by the ring inside said casing, means for displacing said box vertically in the casing in accordance with the range of the target, a carriage carried by the box adapted to be displaced therein according to the speed and range of the target along a radius of the box parallel to the projection of the path of the aircraft, a rod carried by the carriage and pivotally connected with a stationary point of the gun, sighting means carried by said rod, a pinion controlling the radial displacement of the carriage, a rack meshing with the pinion and provided with an outer thread engaging the inner thread of the ring, a cylinder provided with speed curves adapted to rotate with the rack without moving vertically with it, the casing being provided with an aperture allowing the speed curves to be seen and carrying along one edge a scale of ranges, a pointer carried by the box cooperating with the scale on the casing, a speed

control knob controlling the rotation of the cylinder, an inwardly threaded sun-wheel mounted inside the casing and meshing with the outer thread of the ring and a sight control knob controlling the sun-wheel.

In testimony whereof we affix our signatures.
